UNITED STATES PATENT OFFICE.

FREDERICK H. SLOAN, OF HARTFORD, CONNECTICUT.

DESIGN FOR A SPOON, &c.

SPECIFICATION forming part of Design No. 20,537, dated March 3, 1891.

Application filed January 22, 1891. Serial No. 378,703. Term of patent 3½ years.

To all whom it may concern:

- Be it known that I, FREDERICK H. SLOAN, a citizen of the United States, residing at Hartford, in the county of Hartford and State of Connecticut, have invented and produced a new and original Design for Spoons, of which the following is a specification, reference being had to the accompanying drawing, forming a part thereof.
- 10 The figure is a plan view of a spoon of my design, this view illustrating my design.
- The invention relates to the configuration of tea, coffee, sugar, and the other classes of spoons; and the leading feature of my design
- 15 consists in a twig having at one end an enlarged bowl representing a portion of the kernel of the drupe fruit of the tree *Myristica moschata*, more commonly known as the "nutmeg," while the opposite end of the twig, which
- 20 terminates with a representation of the fruit, is bent around in a loop, across which lies a spreading cluster of the leaves of said tree, these forming the enlarged part of the handle.
- The oblong bowl *a* is formed with striations
- 25 or wrinkles radiating from the base to the tip in imitation of the surface of a nutmeg, which

wrinkles may be engraved or etched with the proper shading to effect the wrinkling of a nut or impressed into the metal. The twig *b* extends from the bowl in any graceful curve, 30 and after turning back upon itself, so as to form a loop *c*, terminates in an oval fruit *d*, a portion of which is eaten away, so as to show the wrinkled kernel in the interior near the point where the fruit rests upon the twig. A 35 cluster of leaves *e*, properly veined, is represented as sprouting from the back of the fruit and lying over the loop, so that the leaves and fruit form the enlarged portion of the handle. A stem with a bud or smaller fruit branches from the twig below the larger fruit, 40 so as to give a tapering aspect to the handle as a whole.

What I claim is—

The design for a spoon herein shown and 45 described, the same comprising a wrinkled or striated bowl having a stem terminating in a fruit and cluster of leaves, as set forth.

FREDERICK H. SLOAN.
